UNITED STATES PATENT OFFICE.

RALPH G. SCOTT, OF MILLER, NEBRASKA.

GRAIN-ELEVATOR.

1,284,476.

Specification of Letters Patent. Patented Nov. 12, 1918.

Application filed August 3, 1918. Serial No. 248,152.

To all whom it may concern:

Be it known that I, RALPH G. SCOTT, a citizen of the United States, residing at Miller, in the county of Buffalo, and State of Nebraska, have invented certain new and useful Improvements in Grain-Elevators, of which the following is a specification, reference being had to the accompanying drawings.

10 This invention relates to certain improvements in grain elevators, and it is an object of the invention to provide a device of this general character having novel and improved means whereby the elevator is operated under the influence of the weight of a vehicle when in a position to dump or discharge into a bin or hopper with which the elevator coacts.

Another object of my invention is to provide novel and improved means for operating an elevator which includes a platform supported for swinging movement in a vertical direction and which is adapted to be depressed by the weight of a vehicle positioned upon the platform, together with means whereby power is transmitted to operate the elevator as a result of the downward movement of the platform.

It is also an object of my invention to provide a device of this general character including novel and improved means whereby an elevator is operated under the influence of a platform and adapted to be depressed under the influence of a weight, such as a vehicle, and wherein means are provided for the return of the platform to its upper or normal position when relieved of the weight imposed thereon.

An additional object of the invention is to provide a novel and improved device of this general character wherein the elevator is operated through the medium of a downwardly movable member or platform and wherein the elevator is caused to remain idle upon the upward movement of the member or platform.

The invention consists in the details of construction and in the combination and arrangement of the several parts of my improved grain elevator whereby certain important advantages are attained and the device rendered simpler, less expensive and otherwise more convenient and advanta-

geous for use, as will be hereinafter more fully set forth.

The novel features of my invention will hereinafter be definitely claimed.

In order that my invention may be the better understood, I will now proceed to describe the same with reference to the accompanying drawings; wherein—

Figure 1 is a view in top plan, with portions broken away, of a grain elevator constructed in accordance with an embodiment of my invention;

Fig. 2 is a longitudinal vertical sectional view taken through the device as illustrated in Fig. 1;

Fig. 3 is a view in side elevation with a portion in section of my improved device as herein set forth with the platform in lowered position;

Fig. 4 is a view in end elevation, with a portion broken away and a runway omitted, of my improved device as herein disclosed;

Fig. 5 is a fragmentary view partly in section and partly in elevation illustrating the driving connection between the shaft 15 and the sprocket 22; and

Fig. 6 is a sectional view taken substantially on the line 6—6 of Fig. 5.

As disclosed in the accompanying drawings, P denotes a portable body comprising a pair of transversely spaced runners 1, 85 adapted to travel over the surface of the ground and said runners are maintained in predetermined spaced relation through the medium of the crossed members or braces 2. Extending upwardly from the crossed member or brace 2 adjacent each end of the runners 1 are the transversely spaced uprights 3 connected at their upper end by the transversely disposed bolster or timber 4.

Supported by the timbers 4 are the longitudinally disposed sills 5 in predetermined spaced relation and to which is suitably secured the flooring F.

The intermediate portion of the flooring F is opened and adapted to be normally closed by the vertically swinging platform P. The platform P comprises the longitudinally disposed and transversely spaced sills 6 to which the flooring F' is suitably secured and the rearward end portions of 105 the sills 6 are provided with the depending

boxes 7 through which is disposed a stationary shaft or supporting member 8 held by the forward uprights 2 adjacent the top thereof. The boxes 7 are preferably of a type to contain hard oil or similar lubricant so that the desired swinging movement of the platform P may be obtained with a minimum of frictional resistance. It is also to be understood that when the platform P is at the limit of its upward movement, or in a horizontal position, the floor F' is substantially flush with the floor F.

Engageable with the forward portion of the platform P or that end portion remote from the stationary shaft or supporting member 8 are the latches 10 suitably secured to the floor F or adjacent structure whereby the platform P is maintained in its normal or elevated position. When it is desired to have the platform P swing downwardly, the latches 10 are disengaged from the platform P through the medium of the lever 11 or its equivalent.

Detachably engaged with the opposite ends of the floor F are the runways R which afford means whereby a vehicle loaded with grain or the like may be positioned upon the platform P and whereby said vehicle, after being unloaded, may be readily returned to the ground. It is also to be understood that the platform P is of a length in excess of the length of the vehicle adapted to be positioned thereon and more particularly of a length greater than the wheel base of said vehicle.

Suitably supported by the runners 1 and the adjacent structure carried thereby and below the forward end portion of the floor F, is a bin or hopper H into which the contents of the vehicle are adapted to be dumped or discharged and in order to permit this operation, the portion of the floor F directly above the bin or hopper H is provided with an upwardly and forwardly swinging door 12 which is adapted to be raised after the vehicle has been positioned upon the platform P.

Rotatably supported by the forward uprights 1 and preferably through the medium of the boxings 14, is a shaft 15 provided with a balance wheel 16 to facilitate its rotation. Fixed to the shaft 15 is an outwardly facing cupped member 17 having its peripheral flange 19 overlying a ratchet wheel or gear 20 carried by the inner end portion of the hub 21 of the sprocket wheel 22. Arranged within the cupped member 17 are the pawls or dogs 23 which are constantly urged toward the ratchet wheel or gear 21 whereby it will be perceived that upon rotation of the sprocket wheel 22 in one direction the shaft 15 will be caused to rotate in unison therewith and in the same general direction and whereas upon rotation of the sprocket wheel 22 in the opposite direction,

the shaft 15 remains idle. Contacting with the outer end of the hub 21 is a washer 24 keyed or otherwise secured to the shaft 15. The washer 24 and the cupped member 17 hold the sprocket 22 against movement longitudinally of the shaft 15. Secured to the forward or free end portion of the platform P at one side thereof is a sprocket chain 25 which passes over and meshes with the sprocket 22 and the chain 25 also passes over an idle sprocket 26 supported in advance of the shaft 15. The outer end of the chain 25 is secured to a weight 27, in suspension so that when the platform P is relieved of the weight of a vehicle or the like, the weight 26 will cause the platform P to return to its normal or substantially horizontal position. It will also be self-evident that the weight of the vehicle or the like on the platform P will cause said platform to swing downwardly after the latches 10 have been disengaged from the platform. It is preferred that the latches 10 be constantly urged toward the platform P or more particularly the opening in the intermediate portion of the floor F so that when the platform is returned to its normal or substantially horizontal position under the influence of the weight 26 the latches will automatically engage the platform P to hold the same against depression until required.

E denotes an elevating mechanism comprising an endless carrier 27 disposed around the upper and lower rollers 28 carried by the frame structure 29. The lower roller 28 constitutes a driving element for the endless carrier 27 and said roller has an end portion provided with a gear 31 meshing with the gear 32 fixed to the lower end portion of a vertically disposed shaft 33. The upper end portion of the shaft 33 has fixed thereto a gear 34 meshing with a gear 35 carried by the shaft 15. By this means it will be perceived that as the shaft 15 is rotated by depression or downward swinging movement of the platform P, the endless carrier 27 of the elevating mechanism E will be caused to travel in a direction to carry upwardly or elevate the grain or the like deposited within the bin or hopper H.

Coacting with the shaft 15 is a brake mechanism of any desired type so that the operation of my improved mechanism may be readily controlled.

From the foregoing description, it is thought to be obvious that a grain elevator constructed in accordance with an embodiment of my invention is particularly well adapted for use by reason of the convenience and facility with which it may be assembled and operated and it will also be obvious that my invention is susceptible of some change and modification without departing from the principles and spirit thereof, and for this reason I do not wish to be under-

stood as limiting myself to the precise arrangement and formation of the several parts herein shown in carrying out my invention in practice, except as hereinafter claimed.

5 I claim:

1. A device of the class described comprising a vertically movable platform, a shaft, an elevator, a driving connection between the shaft and the elevator, a sprocket wheel loosely mounted on the shaft, a chain passing over the sprocket and having one end portion secured to the platform, the opposite end portion of the chain being anchored outwardly of the shaft, a weight suspended from the chain outwardly of the shaft, and a member keyed to the shaft and coacting with the sprocket to cause said sprocket to rotate in unison with the shaft upon downward movement of the platform.

20 2. A device of the class described comprising a vertically movable platform, a shaft, an elevator, a driving connection between the shaft and the elevator, a sprocket wheel loosely mounted on the shaft, a chain passing over the sprocket and having one end portion secured to the platform, the opposite end portion of the chain being anchored outwardly of the shaft, a weight suspended from the chain outwardly of the shaft, and a member keyed to the shaft and

coacting with the sprocket to cause said sprocket to rotate in unison with the shaft upon downward movement of the platform, said shaft remaining idle when the platform 35 is elevated by the weight suspended from the chain.

3. A device of the class described comprising a vertically movable platform, a shaft, an elevator, a driving connection between the shaft and the elevator, a sprocket wheel loosely mounted on the shaft, a chain passing over the sprocket and having one end portion secured to the platform, the opposite end portion of the chain being anchored outwardly of the shaft, a weight suspended from the chain outwardly of the shaft, and a member keyed to the shaft, the hub portion of the sprocket being provided with a ratchet gear, a member keyed to the shaft adjacent the sprocket wheel, and a pawl carried by said member and engaging the ratchet gear for causing the sprocket wheel and shaft to rotate in unison upon downward movement of the platform.

40 45 50 55 In testimony wherof I hereunto affix my signature in the presence of two witnesses.

RALPH G. SCOTT.
